ATTORNEY

UNITED STATES PATENT OFFICE

WILLIAM H. SWEETLAND, OF SAN DIEGO, CALIFORNIA

COOLING APPARATUS

Application filed May 22, 1929. Serial No. 365,184.

My present invention relates to cooling apparatus and primarily for cooling air for ventilating purposes and the like.

The objects of this invention are: First, to provide a cooling apparatus adapted for residences, hotels, rooming houses, office buildings, shops, or other buildings housing people, for cooling the temperature of the buildings or the air therein from extremely high to comfortable temperatures; second, to provide an apparatus of this class which may be also used to great advantage for cooling air or other gases for other purposes, such as the preservation of vegetable matter, meats, and the like, where a great drop of temperature is not necessary or desired; third, to provide a cooling apparatus of this class which has unusually large capacity in proportion to its size; fourth, to provide an apparatus of this class which is very economical to operate and one which requires very little attention; fifth, to provide an apparatus of this class which has only one form of core but comprises a multiplicity of such cores positioned side by side and which may be reversed and interchanged, as desired, for forming a zigzag circuitous passage through the cooler for cooling the air, passing therethrough, to a great extent, or for cooling the air to a less degree by merely reversing some of the cores; sixth, to provide an apparatus of this class whereby a large cooling system may be provided by merely combining the separate units into a battery, or by placing batteries of cores end to end in a unitary container or receptacle; seventh, to provide a novel means of supplying water to the cooler and for maintaining a constant level of the water therein for constantly supplying the cores or porous members with moisture; eighth, to provide novel means for sealing the upper portions between the cores and the receptacle against direct passage of air between the inlet and the outlet of the receptacle; ninth, to provide a cooling apparatus in which its large capacity and cooling efficiency is partially effected by a novel arrangement of a blower with relation to the cooling receptacle; and, tenth, to provide an apparatus of this class

which is durable, efficient and which will not readily deteriorate or get out of order.

With these and other objects in view as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which form a part of this application in which:

Figure 1 is a side elevational view of my cooling apparatus in one form of construction; Fig. 2 is a plan view thereof; Fig. 3 is an end view thereof; Fig. 4 is a longitudinal sectional elevational view thereof taken through 4-4 of Fig. 2 and also showing diagrammatically a blower, on a vertical scale, in connection with the intake of the cooling receptacle; Fig. 5 is a transverse sectional view thereof taken through 5-5 of Fig. 4; and, Fig. 6 is an enlarged fragmentary view thereof taken through 6-6 of Fig. 5.

Like characters of reference refer to similar parts and portions throughout the views of the drawings.

My cooler, as illustrated in the drawings, is enclosed in a rectangular receptacle 1 which may be relatively long, depending upon the number of cores or cooling members placed within the receptacle. The receptacle is preferably made of metal so as to be substantially air and water tight. In the form of my cooler as illustrated in the drawings, there is provided at one end an air intake opening or conductor 2 and at the opposite end a discharge opening or conductor 3. The former is positioned near the opposite and near one lateral side, and is connected to the discharge end of a suitable blower 11, while the latter is positioned near the bottom and the opposite lateral side of the receptacle. Within the receptacle is positioned a plurality of the cores or cooling members above mentioned and designated 4 in the drawings. These cooling members extend transversely of the longitudinal extent of the receptacle and are positioned adjacent or against each other and spaced from the end walls of the

receptacle. These cooling members are porous members, preferably moulded integrally from concrete or other suitable material. At the lateral ends of the cooling members are 5 preferably integrally moulded end plates 4a. At the upper and lower ends or sides of the cooling members are heads 4b and 4c. Between the heads of each cooling member is a vertically zigzag wall 4d which extends 10 between the end plates 4a. This zigzag wall forms at the opposite sides thereof and in staggered relation a plurality of horizontal depressions or channels in the opposite sides of the cooling members, as shown best in 15 Fig. 4. When two of the cooling members are positioned with their sides adjacent each other, there is formed between two adjacent cooling members a wide vertically zigzag channel A. Through the zigzag wall of each 20 cooling member, and transversely with respect to said cooling members, is a plurality of holes 4e which connect the opposite sides of the cooling members and also connect the horizontal depressions or channels at the opposite sides thereof. These holes 4e are arranged in only one-half, or less than one-half of the cooling member and at one side only of the horizontal median plane passing therethrough. Thus, when air passes into 25 the conductor 2, it passes downwardly between the end wall of the receptacle and the first cooling member, and then passes through the transverse holes 4e in the lower half of the first cooling member, then passes upwardly through the wide vertically zigzag 30 channel A, then passes through transverse holes in the upper half of the second cooling member, then downwardly into the next vertically zigzag passage A and so on until the 35 air is finally discharged through the conductor or opening 3. In each head 4b and 4c is provided a horizontal depression or recess 4f which extends longitudinally with respect to the cooling member. These 40 depressions, aside from lightening the bulk and weight of the cooling or porous members, provide depressions or reservoirs at the upper sides of the cooling or porous members for receiving and containing water, which 45 water is adapted to seep from such reservoir through the pores, crevices, and interstices of the cooling or porous members until substantially the whole of the exposed surface of the member 4 is moisture laden and adapted to be impinged and evaporated by the air 50 coming in contact with such surface and passing through the various channels in the apparatus. Thus it will be seen that the cores or cooling members are or may be made 55 of identical construction but merely reversed, that is, the normally lower side of one is positioned in reverse order and coincident with the normally upper sides of adjacent and alternate members 4.

60 The top or cover portion of the receptacle

is provided with a multiplicity of downwardly extending portions 1a which in this instance are depressions, there being as many depressions as cooling members. These depressions 1a extend into the longitudinal depressions or recesses 4f at the normally upper sides of the members 4 and extend also into the water therein so as to seal substantially the space between the upper portion of the receptacle and the upper sides of the members 4 against the passage of air from the inlet to the outlet of the receptacle over the upper sides of the cooling members. 70

The bottom of the receptacle is preferably 80 filled with water so as to seal as much as possible the spaces between the lower portions of the cooling members and the bottom of the receptacle.

The means for maintaining a constant level of water, or a constant supply of water in the 85 depressions or recesses 4f at the upper sides of the cooling members, may consist of a manifold 5, a receptacle 6 and a cock 7. The manifold 5 is provided with a plurality of downwardly extending outlets 5a which extend into the depressions 4f and normally below the level of the water therein but above the lower portions of the depressions 1a. The manifold is provided with an inlet 5b above the main portion of the manifold, 90 said inlet being in the form of a socket. Into this socket is adapted to fit the mouth of a bottle or other suitable receptacle 6 for supplying water to the manifold. In the manifold between the lower portion thereof and 100 the tapered inlet 5b is positioned the cock 7 which is preferably closed only when desiring to re-fill or re-place the receptacle 6. With this apparatus, it will be seen that as soon as some of the water in any one of the 105 depressions 4f seeps into the cooling or porous member and the level of the water within the depression 4f is lowered below the lower end of the outlet 5a extending therein, water is 110 discharged by gravity into such depression until the level thereof is positioned above the lower end of the outlet 5a.

In the side walls of the depressions 1a may be provided a glass plate 8, as shown best in Fig. 6, for visibly indicating the level of the 115 water in the respective depressions or recesses 4f.

As the warm or hot air from the room or outside is forced into the inlet 2 and through the various circuitous and zigzag passages in 120 which all surfaces are moisture laden, the moisture or water is evaporated, cooling the air to a marked degree and discharging said cool air from the outlet 3. It will be noted that if less cooling is desired, alternate cores 125 or cooling members may be reversed by merely removing the cover, thus materially shortening the path of the air through the apparatus and the exposure of the moisture there- 130 to.

I have found that by blowing the air through the cooling receptacle, the circulating air is brought into contact with all portions of the receptacle and cooling members and the air is cooled more quickly and to a lower temperature than when the air is exhausted from the receptacle by connecting the suction end of the blower to the discharge opening or conductor 3.

Though I have shown and described a particular construction, combination and arrangement of parts and portions, I do not wish to be limited to this particular construction, combination and arrangement, but desire 15 to include in the scope of my invention the construction, combination and arrangement substantially as set forth in the appended claims.

Having thus described my invention, what 20 I claim as new and desire to secure by Letters Patent is:

1. In an apparatus of the class described, a receptacle having inlet and discharge openings, and a plurality of porous members positioned side by side therein, there being provided between said porous members air 25 passages connected at their opposite ends to alternate adjacent air passages forming a substantially circuitous zigzag air passage 30 between the inlet and the outlet openings.

2. In an apparatus of the class described, a receptacle having inlet and discharge openings, and a plurality of porous members positioned side by side therein, there being provided between said porous members air passages connected at their opposite ends to alternate adjacent air passages forming a substantially circuitous zigzag air passage between the inlet and the outlet openings, said 35 porous members having depressions at their upper ends for receiving and containing water and for supplying a constant source of moisture to the porous members.

3. In an apparatus of the class described, a 40 receptacle having inlet and discharge openings, a plurality of porous members positioned side by side therein, there being provided between said porous members air passages connected at their opposite ends to alternate adjacent air passages forming a substantially circuitous zigzag air passage between the inlet and the outlet openings, said porous members having depressions at their 45 upper ends for receiving and containing water and for supplying a constant source of moisture to the porous members, and a manifold positioned at the upper portion of the receptacle and connected with a source of water above the manifold and at substantially 50 atmospheric pressure, said manifold having a multiplicity of outlets extending into the recesses at the upper ends of the porous members and normally below the level of the water in the recesses.

4. In an apparatus of the class described, a

receptacle having inlet and discharge openings, a plurality of porous members positioned side by side within the receptacle, there being provided between the porous members a continuous air passage from the inlet to the outlet opening, said porous members having at their upper sides recesses adapted to contain water for constantly supplying moisture to the porous members, and a manifold positioned at the upper portion of the receptacle 70 and connected with a source of water above the manifold and at substantially atmospheric pressure, said manifold having a multiplicity of outlets extending into the recesses at the upper ends of the porous members and normally below the level of the water in the recesses.

5. In an apparatus of the class described, a receptacle having inlet and outlet openings, a plurality of porous members positioned side by side therein, there being provided between the porous members air-cooling passages, and the alternate porous members having transverse openings at their coincident ends, connecting each air passage at the opposite ends to alternate air passages forming a zigzag air-cooling passage between, through and in contact with the porous members from the inlet to the outlet openings of the receptacle.

6. In an apparatus of the class described, a receptacle having inlet and outlet openings, a plurality of porous members positioned side by side therein, there being provided between the porous members air passages, and the alternate porous members having transverse openings at their coincident ends, connecting each air passage at the opposite ends to alternate air passages forming a zigzag air passage between the inlet and outlet openings of the receptacle, said porous members being of identical construction, the adjacent porous members being positioned in reverse order in the receptacle.

7. In an apparatus of the class described, a receptacle having inlet and outlet openings, a plurality of porous members positioned side by side therein, there being provided between the porous members air passages, and the alternate porous members having transverse openings at their coincident ends, connecting each air passage at the opposite ends to alternate air passages forming a zigzag air passage between the inlet and outlet openings of the receptacle, the upper sides of the porous members being provided with longitudinal depressions for receiving and containing water for constantly supplying moisture to the porous members.

8. In an apparatus of the class described, a receptacle having inlet and outlet openings, a plurality of porous members positioned side by side therein, there being provided between the porous members air passages, and the alternate porous members having transverse

- openings at their coincident ends, connecting each air passage at the opposite ends to alternate air passages forming a zigzag air passage between the inlet and outlet openings 5 of the receptacle, the upper and lower sides of the porous members being provided with depressions, said porous members being of substantially identical construction and the adjacent porous members being positioned in reverse order, the depressions at the normally upper sides of the porous members being adapted to receive and contain a supply of water for constantly supplying the porous members with moisture.
- 10 9. In an apparatus of the class described, a receptacle having an inlet and an outlet opening, and a plurality of interchangeable and reversible porous members forming between each other air passages communicating at their opposite ends with the coincident ends of adjacent passages and forming a long substantial zigzag continuous air passage between the inlet and outlet openings.
- 15 10. In an apparatus of the class described, a receptacle having an inlet and an outlet opening, and a plurality of interchangeable and reversible porous members forming between each other air passages communicating at their opposite ends with the coincident ends of adjacent passages and forming a substantial zigzag continuous air passage between the inlet and outlet openings, said porous members having at their opposite upper and lower sides longitudinal depressions, the depressions at the upper sides being adapted to receive and contain water for supplying the porous members constantly with moisture.
- 20 11. In an apparatus of the class described, a receptacle having inlet and outlet openings, and a plurality of porous members positioned side by side within the receptacle, the intermediate portions of the porous members having zigzag walls and corresponding staggered depressions at the opposite sides of the zigzag walls, the depressions at the adjacent sides of adjacent porous members being positioned in overlapped relation forming a zigzag passage between adjacent porous members, the opposite ends of the zigzag passages communicating with coincident ends of alternate adjacent zigzag passages.
- 25 12. In an apparatus of the class described, a receptacle having inlet and outlet openings, and a plurality of porous members positioned side by side within the receptacle, the intermediate portions of the porous members having zigzag walls and corresponding staggered depressions at the opposite sides of the zigzag walls, the depressions at the adjacent sides of adjacent porous members being positioned in overlapped relation forming a zigzag passage between adjacent porous members, the alternate ends of adjacent porous members being provided with a multiplicity

of transverse holes connecting the opposite ends of the zigzag passages with the coincident ends of adjacent alternate zigzag passages forming also a general zigzag circuitous passage between the several porous members between the inlet and outlet openings of the receptacle.

13. In an apparatus of the class described, a receptacle having inlet and outlet openings, a plurality of porous members positioned side by side within the receptacle and having air passages therebetween connected at their opposite ends with the coincident ends of adjacent and alternate passages, said porous members having at their upper sides depressions for receiving and containing water, the upper portion of the receptacle having downwardly extending portions extending into said depressions and the water therein for sealing the upper portion of the receptacle against direct communication between the inlet and outlet openings.

14. In an apparatus of the class described, a receptacle having inlet and outlet openings, a plurality of porous members positioned side by side within the receptacle and having air passages therebetween connected at their opposite ends with the coincident ends of adjacent and alternate passages, said porous members having at their upper sides depressions for receiving and containing water, the upper portion of the receptacle having downwardly extending portions extending into said depressions and the water therein for sealing the upper portion of the receptacle against direct communication between the inlet and outlet openings, and a manifold positioned at the upper portion of the receptacle, communicating with a source of water and provided with a multiplicity of outlets extending through the top of the receptacle into said depressions and terminating above the lower portions of the portions of the receptacle extending into said depressions.

15. In a cooling apparatus, a cooling receptacle having inlet and discharge openings, a moisture conducting means positioned within the receptacle and provided with a plurality of adjacently positioned relatively sharp angular zigzag air passages therein, said passages being connected at their opposite ends to alternate adjacent air passages forming a long continuous irregular and interrupted air passage in said means between the inlet and discharge openings, a water supply means in association with the last mentioned means for supplying the same with moisture, and a blower connected with its discharge to the intake opening of the receptacle and adapted to blow air through said long continuous passage.

16. In a cooling apparatus, a cooling receptacle having inlet and discharge openings, and a moisture conducting means positioned

within the receptacle and provided with a plurality of adjacently positioned relatively sharp angular zigzag air passages therein, said passages being connected at their opposite ends to alternate adjacent air passages forming a long continuous irregular and interrupted air passage in said means between the inlet and discharge openings.

In testimony whereof, I have hereunto set my hand at Los Angeles, California, this 14th day of May, 1929.

WILLIAM H. SWEETLAND.
